(57) **CLAIM**

The ornamental design for a biological cell processing chip, as shown and described.

DESCRIPTION

FIG. 1 is an isometric view of an example embodiment of a fluid channel of a biological cell processing chip layer in accordance with our new design;

FIG. 2 is a front elevation view thereof;

FIG. 3 is a rear elevation view thereof;

FIG. 4 is an isometric view of another example embodiment of a fluid channel of a biological cell processing chip layer in accordance with our new design;

FIG. 5 is a front elevation view thereof; and,

FIG. 6 is a rear elevation view thereof.

The details shown in broken lines are for illustrative purposes only and form no part of the claimed design.
